UNLOADING APPARATUS FOR DUMP TRUCKS

Lindsay S. Wall, Winston-Salem, N. C.

Application May 28, 1949, Serial No. 95,993

6 Claims. (Cl. 214—83.26)

1

This invention relates to vehicular dump trucks and the like and more especially to an unloading apparatus adapted to be connected to the rear end of the frame of the truck and comprising a longitudinally movable supporting frame for a gear box mounted on the rear end of the chassis of the truck and having a universal mounting thereon for supporting one end of a conveying apparatus, whereby the gear box may be moved to a position where it will be disposed below the discharge end of the truck bed when it is desired to remove the contents of the truck bed by tilting or raising the front end of the same, so as to cause the contents therein to slide out of the rear portion of the bed of the truck by gravity as well as for delivering the contents to a point remote from the truck.

There are many types of trucks now employed for transporting aggregate such as sand, crushed stone, coal and the like, from one place to another and the beds of which are pivotally connected adjacent the rear end of the chassis of the truck and having means for raising the front end of the bed of the truck so as to dump the contents of the bed of the truck rearwardly of the same. There are many other trucks employed having beds which are fixed to the chassis of the truck throughout their lengths and having various types of conveying means extending along the bottom portion of the bed for emptying the contents of the bed of the truck rearwardly of the same and thus eliminating the necessity of tilting the truck bed for removing the contents therefrom.

However, for all practical purposes, particularly in transporting coal from a coal yard to a home, it has been necessary to provide trucks having a non-tiltable bed with a suitable conveying or discharging apparatus at the rear end thereof onto which the conveying means disposed at the bottom portion of the bed would direct the aggregate from within the bed and for carrying the contents from the rear end of the bed to points some distance away from the truck and which may be inaccessible to the truck.

It has not been possible, however, to mount a conveying apparatus at the rear of the dump bed type of truck which would carry the contents discharged from the dump bed of the truck to a point remotely disposed from the same, other than by the use of a sheet metal chute or the like.

It is therefore an object of this invention to provide an unloading motor truck having a dump bed mounted thereon with a gear housing having a train of gears therein and a connection between the gear housing and the power take-off of the truck and to provide a universal mounting on the gear housing which is adapted to receive one

2

end of a discharge conveyor which is removably connected thereto, this end of the conveyor normally being disposed immediately below the opening at the rear of the bed through which the contents are discharged onto the conveyor.

It is another object of this invention to provide an unloading motor truck of the type described in which the gear housing is telescopically mounted at the rear of the chassis of the truck and the delivery conveyor being removably secured to the universal mounting, so the delivery conveyor may be removed from the same and the universal mounting along with the gear housing may be moved to a position beneath the rear end of the bed of the truck and out of vertical alignment with the opening at the rear end of the bed when the bed is in a tilted position for emptying the contents rearwardly of the truck without the use of a discharge conveyor in the truck bed.

It is another object of this invention to provide an apparatus of the type described for use with motor vehicular trucks, the truck being provided with hydraulically operable means for raising the front end of the dump bed of the truck and to provide control means at the rear of the truck and connections between the same and the hydraulically operable means for tilting the bed and other control means adjacent the same for controlling the conventional clutch means which normally engages the power take-off of the truck so an operator may control the raising and lowering of the front end of the dump bed of the truck and also the starting and stopping of the discharge conveyor from the rear of the truck.

It is another object of this invention to provide in a motor vehicular truck of the class described a power transmission unit disposed intermediate the conventional power take-off and the gear box and having a gear train therein. The transmission unit is also disposed intermediate the power take-off and the motor for the hydraulically operable means for raising and lowering the front end of the bed of the truck and comprises a gear housing secured to the truck and having a pair of intermeshing gears therein, so they will

turn in opposite directions, one of the gears fixedly mounted on a shaft extending through opposed ends of the housing, the ends of the shaft being provided with universal joints for connecting one end with the shaft from the power take-off and for connecting the other with a shaft extending to the gear housing for the delivery conveyor apparatus, and the other of the gears being fixedly mounted on a shaft extending through one of the walls of said housing and having a universal joint thereon for connecting the same to a second shaft extending to the motor for operating the hydraulically oper-

able means for raising the front end of the truck bed.

It is another object of this invention to provide a modified means for transmitting motion from the power take-off to the hydraulic motor and also to the gears disposed within the gear housing for the conveyor mechanism comprising a housing having a pair of sprocket wheels therein and a sprocket chain connecting the sprocket wheels so they both turn in the same direction, one of the sprocket wheels being mounted on a shaft extending out of the housing at both its rear and front ends, and being connected at one end to the shaft from the power take-off while the other end is connected to a shaft extending to the gear housing for driving the delivery conveyor. The other of the sprocket wheels is fixedly mounted on a shaft which extends rearwardly only from the housing and is connected by a universal joint to a shaft extending to the hydraulic motor which is instrumental in the raising and lowering of the front end of the dump truck bed.

Some of the objects of the invention having been stated, other objects will appear as the description proceeds, when taken in connection with the accompanying drawings, in which—

Figure 1 is a top plan view of a truck on the chassis of which a dump bed is mounted and showing the delivery conveyor apparatus connected thereto and showing various connections between the conveyor apparatus and the power take-off of the truck, the front portion of the truck being broken away;

Figure 2 is an elevation taken along the line 2—2 in Figure 1, showing the power take-off mechanism associated with the conventional transmission of the truck;

Figure 3 is a sectional plan view showing the connection between the power take-off of the truck and the transmission and is taken substantially along the line 3—3 in Figure 2;

Figure 4 is an enlarged elevation of the truck looking up at the lower side of Figure 1 but omitting the conveying apparatus and showing the dump truck bed in a horizontal position;

Figure 5 is a rear elevation of the truck looking from the right-hand side of Figure 4 to the left;

Figure 6 is an enlarged elevation of an intermediate gear housing showing the manner in which it is secured to the chassis of the truck and is taken substantially along the line 6—6 in Figure 4;

Figure 7 is a fragmentary view of the right-hand lower portion of Figure 4 but showing the dump truck bed in a tilted position and showing the universal mounting for the conveyor positioned beneath the chassis of the truck;

Figure 8 is an enlarged vertical sectional view taken substantially along the line 8—8 in Figure 7 and showing the stationary side rails for supporting the gear housing with the universal mounting for the conveyor;

Figure 9 is an enlarged elevation with parts broken away and showing other parts in section and is taken substantially along the line 9—9 in Figure 5 and showing the manner in which the movable frame is mounted in the pivoted frame for supporting the universal mounting for the conveyor;

Figure 10 is a side elevation similar to Figure 4, with parts in section, and showing the rear portion of the truck but omitting the wheel on the side nearest the observer, and showing the truck

body in a tilted position and also showing the detachable delivery conveyor frame mounted on the universal mounting;

Figure 11 is an enlarged elevation of the universal mounting and the conveyor associated therewith and showing the supporting means for the universal mounting in cross section and is taken substantially along the line 11—11 in Figure 10;

Figure 12 is a vertical sectional view partly in section and showing the gear box of the universal mounting and associated parts and is taken along the line 12—12 in Figure 11;

Figure 13 is a fragmentary vertical sectional view taken along the line 13—13 in Figure 11 and showing the feed end of the detachable delivery conveyor;

Figure 14 is an enlarged vertical sectional view showing the manner in which the movable frame is mounted in the pivoted frame and is taken along the line 14—14 in Figure 7;

Figure 15 is an elevation with parts broken away looking substantially along the line 15—15 in Figure 6;

Figure 16 is a vertical sectional view taken along the line 16—16 in Figure 15 but showing a modified form of power transmission means from that shown in Figure 6;

Figure 17 is a vertical sectional view through the gear housing and the universal mounting and is taken substantially along the line 17—17 in Figure 12;

Figure 18 is a top plan view showing the rear portion of the chassis of the truck and showing the lever arms for supporting the truck bed while in a tilted position in cross section and looking substantially along the line 18—18 in Figure 10.

Referring more specifically to the drawings, the numeral 10 designates the rear wheels of a suitable motor truck which are mounted on the outer ends of axles 9 disposed in the conventional axle housing 11. The truck also has a pair of front wheels which are not shown. The axle housing 11 has mounted thereon conventional springs 12 for supporting the conventional chassis frame of the truck, broadly designated at 13.

The chassis frame 13 comprises side frame members 14 and 15, an intermediate cross frame member 16 and a rear cross frame member 17 (Figures 5 and 18). Suitable tie bolts 20 secure an auxiliary frame, broadly designated at 21, to the upper surface of the chassis frame 13. This auxiliary frame 21 comprises side frame channel members 22 and 23, a front cross frame angle bar 24 and a rear cross frame bar 25 which is bent inwardly at its central portion in Figure 18 and is connected to the rear ends of spaced tie bars 26 and 27 by any suitable means such as bolts 30.

The front ends of the tie bars 26 and 27 are secured as by bolts 31 to the vertical portion of the horizontally disposed cross frame member 24. Spaced transverse shafts 33 and 34 are fixedly mounted in the longitudinally extending channel bars 22 and 23 of the auxiliary frame 21. The purpose of these shafts 33 and 34 will be later described. There is a third transverse shaft 35 extending between the channel bars 22 and 23 and being fixedly mounted therein and on opposed ends of which conventional support brackets 37 and 38 are pivotally mounted, these brackets 37 and 38 being a part of a conventional dump truck bed broadly designated at 40.

The support brackets 37 and 38 are secured as by bolts 42 to longitudinally extending channel

bars 43 and 44 (Figure 5) which normally rest on the upper flanges of the channel bars 22 and 23 of the auxiliary frame 21 when the dump truck bed 40 is in the horizontal position shown in Figure 4. Suitable guide members 45 and 46 are shown in Figures 4 and 18 as being welded to the remote surfaces of the channel bars 22 and 23 of the auxiliary frame 21 to assist in locating the front end of the dump truck bed 40 in proper alignment with the auxiliary frame 21 when in lowered position as shown in Figure 4.

The bed 40 also comprises side panels 50 and 51, the front ends of which in Figure 1, are welded to a front panel member 52 and the rear ends of which are connected in a conventional manner to a rear panel or gate 53. The side panels 50 and 51 are provided with suitable reinforcing gusset members 55, the lower edges of which, in Figures 4 and 5, are suitably connected to horizontally disposed plate members 60 and 61 extending longitudinally at opposed sides of the dump truck bed 40.

The side walls 50 and 51 and the front and rear walls 52 and 53 are supported at their lower ends on a horizontally disposed bottom plate 63 which is, in turn, secured in a conventional manner to the upper flanges of the longitudinally extending channel bars 43 and 44 as shown in Figure 5.

In order to facilitate the use of the conventional truck bed 40 with the present invention, I have provided an opening 64 in the lower central portion of the rear panel 53 of the bed 40, at opposed sides of which vertically disposed guide rails 65 and 66 (Figure 5) are welded to the rear panel 53 and extend from its upper to its lower edges.

Mounted for frictional sliding movement between the vertically disposed guide members 65 and 66 in Figure 5 is a door 67 which is adapted to normally close the opening 64. This door 67 has a link 70 pivotally connected thereto as at 71 (Figure 5) to the lower end of which a lever arm 72 is pivotally connected as at 73. This lever arm 72 is oscillatably mounted intermediate its ends as at 75 on the vertically disposed guide rails 66. The lever arm 72 extends a substantial distance beyond the point 75 in Figure 5 and has an outwardly and upwardly bent handle portion 76 integral therewith for manipulation of the lever arm 72 by the operator of the truck for raising or lowering the door 67 when it is desired to empty the contents from within the truck bed 40. A pair of spaced L-shaped brackets 77 and 78 are welded to the plate 60 and are provided to serve as a storage rack for the detachable conveyor, to be later described, when it is not in use.

Referring to Figures 1, 7, 10 and 18 there is shown a conventional hydraulic apparatus broadly designated at 80 for controlling the raising and lowering of the truck bed 40 from the position shown in Figure 4 to the position shown in Figure 10 and vice versa, and a detailed description of which is given in U. S. Patents Numbered 1,760,808, 1,893,124, and 1,893,125. Therefore, only a brief description will be given of this hydraulic apparatus.

The hydraulic apparatus 80 comprises a cylinder 81 having a suitable piston 82 mounted for longitudinal reciprocation therein and from which a piston rod 84 extends. The upper free end of the piston rod 84 in Figures 7 and 10 is threadably imbedded in a cross arm 85 (Figure 18), opposed ends of which are restricted as at 86 and each restricted end 86 slidably penetrates the rearmost portions of substantially triangularly-shaped built-up arms 87 and 87'.

The lower ends of the arms 87 and 87' are oscillatably mounted on the intermediate transverse shaft 34 and the upper portions of the triangularly-shaped arms 87 and 87' have opposed ends of shafts 92, 93 and 94 suitably secured thereto. Referring to Figure 10, it may be noted that the shaft 92 is pivotally connected to a plate member or bracket 96 which is pivotally connected as at 97 to the bottom plate 63 of the truck bed 40 and which has an arcuate slot 100 therein slidably penetrated by the shaft 93. The plate 96 also has a notch 102 therein which is adapted to engage the shaft 94 when the bed 40 is in the horizontal position shown in Figure 4.

Referring again to Figures 1 and 18, it may be observed that the lower end of the cylinder 80 is oscillatably mounted on the foremost of the transverse shafts 33 secured in the auxiliary frame 21, all of which is clearly shown in U. S. Letters Patent No. 1,893,125 of January 3, 1933. A suitable hydraulic pump 105 is secured to the lower end of the cylinder 81 and also communicates with the interior thereof and a return pipe 106 is connected at its upper end adjacent the upper end of the cylinder 81 and at its lower end to the hydraulic pump 105. A suitable valve mechanism 107, only the housing of which is shown in Figure 18, is disposed between the hydraulic pump 105 and the lower end of the cylinder 81 and has a control arm 110 secured to the upper end thereof. This valve mechanism is clearly shown in the said Patent No. 1,893,125. The lower end of the control arm 110 in Figures 1 and 18 has one end of a connecting rod 111 pivotally connected thereto, the other end of the connecting rod being pivotally connected to the inner end of a short lever arm 113 which is a part of the present invention. This lever arm 113 is preferably oscillatably connected to the lower surface of the longitudinally extending brace bar 26 intermediate its ends and has the front end of a control rod 114 connected thereto. This control rod 114 extends rearwardly at a slightly lower elevation than the transverse shafts 33 and 34 and slidably penetrates the rear transverse frame member 17 of the chassis 13 (Figure 5) and has a vertically extending handle member 115 secured thereto as by welding.

The conventional hydraulic motor pump 105 in Figure 18 is driven by a conventional shaft 120 extending from the lower end thereof and being connected, by a universal joint 121, to a rearwardly and downwardly extending shaft 122. The front end of the shaft 122 is connected, as by a universal joint 123, to the rear end of a stub shaft 124 which extends forwardly and is rotatably mounted in a semi-circular casing 125 of a gear housing broadly designated at 127. This gear casing 125 is flanged and secured as by bolts 130 (Figure 6) to a tubular block member 131, to the opposite side of which a second semi-circular casing 132 is secured by the same bolts 130 which secure the casing 125 to the tubular block 131 (Figures 6 and 15). The block 131 of the gear housing 127 is supported by an angle clip 134 secured thereto as by a screw 135, the upper end of the angle clip 134 being secured, as by welding, to the lower surface of the transverse frame member 16 of the chassis 13. The block 131 is also supported by a strap iron member 136, secured to the lower surface of the block 131 as by a screw 137. The strap iron member 136 extends

outwardly in Figure 6 and is welded to the outer surface of the web portion of the longitudinally extending channel bar 15 of the truck chassis 13 to thus secure the gear housing 127 to the truck chassis 13.

A pinion 140 is fixedly mounted on the shaft 124 within the gear housing 127 (Figure 6) and meshes with a pinion 141 fixedly mounted on a longitudinally extending shaft 142 rotatably mounted in the casing 132 of the gear housing 127. It is thus seen that the pinion 140 will rotate in the opposite direction from the pinion 141 for imparting rotation to the conventional parts of the gear pump 105.

However, in the event that the conventional parts of the pump 105 must rotate in the same direction as the shaft 142, a modified means of transmitting rotation from the shaft 142 to the shaft 124 is shown in Figure 16. In the modified form of this portion of the invention, like parts will bear like reference characters to the parts shown in Figure 6, inasmuch as the modified form merely comprises a pair of sprocket wheels 145 and 146 which are interconnected by a sprocket chain 147, the sprocket wheels 145 and 146 being fixedly mounted on the shafts 124 and 142, respectively.

In the modified means for transmitting rotation from the shaft 142 to the shaft 124 it is obvious that rotation in a like direction will be imparted to both of the shafts 124 and 142 while in the original form shown in Figure 6, rotation in the opposite direction would be transmitted from the shaft 142 from that imparted to the shaft 124.

The front end of the shaft 142 in Figure 1 is connected by a universal joint 150 to a forwardly extending shaft 151, the front end of which is connected to a shaft 152 by a universal connection 153 which is similar in all respects to the universal connection 150.

The shaft 152 is a conventional power take-off shaft and is rotatably mounted in a conventional housing 155 of the power take-off unit (Figures 1, 2 and 3).

This housing 155 is secured by bolts 156 to a conventional transmission housing 157 of a motor vehicle. The shaft 152 has an enlarged splined portion 160 on which is keyed a gear 161. This gear 161 is normally in engagement with a constantly rotating gear 162 of the transmission when the power take-off unit is delivering power to the shaft 151. However, when the shaft 151 is not in operation, the gear 161 is moved out of engagement with the gear 162. The means for moving the gear 161 back and forth, in and out of engagement with the gear 162, is effected by means of a suitable forked yoke 163 which has suitable prongs 164 extending adjacent opposed sides of the gear 161. The yoke 163 is fixedly mounted on a shaft 165, which, in turn, is slidably mounted in the power take-off housing 155.

Pivottally connected to the left-hand end of the shaft 165, as at 166, is an upwardly extending lever 167. This lever 167 is pivoted intermediate its ends as at 170 to a projection 171 extending laterally from the housing 155. When it is desired to move the gear 161 out of engagement with the gear 162, it is only necessary to partially rotate the lever 167 in a clockwise direction in Figure 2, thereby causing the shaft 165 and its associated yoke 163 to move the gear 161 to the left in Figure 13 upon the splined portion 160 of the shaft 152 and thereby cause it to become disengaged from the gear 162.

In order to facilitate the moving of the gear 161

161 along the splined portion 160 of the shaft 152, so as to move the same into and out of engagement with the gear 162, it is obvious that rotation of the gear 162 must be temporarily stopped. Therefore, I have provided a mechanism adapted to operate the conventional clutch mechanism of trucks of this type such as is described in the patent to R. E. Wall, No. 2,284,853 of June 2, 1942 and which is shown in Figures 1 and 10 of said patent. The conventional clutch pedal 175 is pivoted as at 176 in a conventional manner. An extension 177 is provided on the lower portion of the clutch pedal 175 to which is pivoted, as at 180, the front end of a link 181.

15 The link 181 extends to the rear of the truck, slidably penetrates the horizontally disposed frame member 17 of the chassis 13, and has a vertically disposed handle member 182 (Figure 5) secured to the free end thereof as by welding 20 for engagement by the hand of an operator. When the link 181 is pulled to the right in Figure 1, the clutch pedal 175 will be swung on its pivot to disengage conventional clutch mechanism, not shown, associated with trucks of this 25 type to thus permit the rotation of the gear 162 to cease so as to permit the gear 161 to be moved into or out of engagement with the gear 162 by manipulation of the lever 167.

Referring again to the shaft 142, it may be 30 observed in Figures 1 and 18 that it extends rearwardly and is connected to a rearwardly extending shaft 185 by a universal connection 186. The rear end of the shaft 185 is connected, by a universal connection 187 identical to the 35 universal connection 150, to a tubular shaft 190 which is preferably polygonal in cross section and which has a conforming shaft 192 mounted for longitudinal sliding movement therein (Figures 1 and 18). The front end of the shaft 185 40 in Figure 18 is supported by the shaft 142 and the rear end of the shaft 185 is rotatably mounted in a suitable bearing block 193 suitably secured to the longitudinally extending channel bar 15 of the chassis frame 13.

45 The shafts 190 and 192 extend rearwardly and downwardly at an angle and the shaft 192 is connected by a universal joint 195 (Figures 1 and 18) to a stub shaft 196 rotatably mounted in a forwardly projecting portion 197 of a gear housing 200. The shaft 196 extends into the housing 200 and has a beveled gear 201 fixedly mounted on its end which cooperates with a large gear 202 having lower and upper beveled gear toothed 50 surfaces 203 and 204, respectively, the beveled 55 gear 201 meshing with the lower beveled gear teeth 203.

The gear 202 has lower and upper hub portions 206 and 207 integral therewith, the remote ends 60 of which engage the bottom of the housing 200 and the lower surface of a universal mounting cap member or housing 210. The upper edge of the housing 200 and the lower edge of the cover member 210 are provided with coinciding annular grooves so the cover 210 may rotate on the housing 200 and may be held in axial alignment with the same.

65 The gear 202 is rotatably mounted on a vertically disposed shaft 211 which slidably penetrates the lower and upper housings 200 and 210 and has one or more suitable nuts 213 threadably mounted on one or both ends thereof for securing the portions 200 and 210 together.

The manner in which the gear housing 200 is

feature of this invention and will be later described in detail.

Referring to Figure 17 it may be observed that the universal mounting cover 210 has a substantially semi-circular hollow portion 215 to provide space in which a bevelled gear 216, meshing with the upper toothed portion 204 of the gear 202, is disposed.

This gear 216 is fixedly mounted on one end of a shaft 217 rotatably mounted in an outwardly projecting bearing portion 220 integral with the cover member 210. This outwardly projecting portion 220 is preferably circular in cross section and has a flanged portion 221 of an angularly disposed chain guard housing 222 secured thereto by any suitable means such as screws 219. This chain guard housing 222 is capped by a similarly shaped cap member 223 secured thereto as by bolts 224. The shaft 217 slidably penetrates the chain guard housing 222 and has a sprocket wheel 225 fixedly mounted on the right-hand end thereof in Figure 17.

The sprocket wheel 225 has a sprocket chain 226 mounted thereon which meshes with a sprocket wheel 227 fixedly mounted on a shaft 230 rotatably mounted in the chain guard housing 222 and its cover member 223. The shaft 230 extends out of the cover 223 and has a suitable hand wheel 232 fixedly mounted thereon. The shaft 230 also extends through the housing 222 and has a female clutch member 233 fixedly mounted thereon provided with a plurality of bores 234 which are adapted to slidably receive pins 265 of a mating clutch dog member to be later described and which is a part of the conveyor apparatus which may be removably connected to the universal mounting housing 210.

Secured to the outer surface of the chain guard housing 222, as by screws 240 (Figures 12 and 17) is a built-up Z-shaped bracket 241 of welded construction having a semi-circular cavity or notch 242 in the upper surface of its upper leg.

The cover member 210 in Figure 17 has an outwardly projecting portion 244 integral therewith, to the outer surface of which an upwardly and forwardly extending angularly disposed arm 245 is secured, as by screws 246, and the arm 245 has a semi-circular cavity or notch 247 therein which is in transverse alinement with the cavity 242 in the bracket 241. The semi-circular notches 242 and 247 in bracket 241 and arm 245, respectively, are adapted to slidably receive bearing members 250 and 251, respectively, of a delivery conveying apparatus broadly designated at 252 (Figure 11). The structure of the conveying apparatus 252 and the manner in which it is connected to the universal mounting 210 are very similar to that shown in my co-pending application entitled Improved Unloading Truck, Serial Number 51,419, filed September 27, 1948 and now Patent No. 2,520,291, granted August 29, 1950.

The bearing members 250 and 251 in Figure 11 penetrate brackets 253 and 254, respectively, which may be integral therewith or may be welded thereto as shown in Figure 11. The brackets 253 and 254 are identical, the bracket 253 also being shown in Figure 13. The bracket 253 is adapted to engage the inner surface of the built-up Z-shaped bracket 241 when the bearing member 250 is inserted in its cavity 242. However, the bracket 254 on the bearing member 251 is spaced a substantial distance apart from the proximate surface of the angularly disposed arm 245 when the bearing member 251 is seated in the semi-circular cavity 247. Therefore, there has been

provided an arm 256 (Figure 4) which is pivotally connected as at 257 to the inner surface of the arm 245 and a wider curved portion 260 is integral with the arm 256 and conforms to the shape 5 of the bearing member 251 so that upon moving the portion 260 against the member 251, the conveyor 252 is locked as to endwise movement of the bearing members 250 and 251 in engagement with the members 241 and 245. The curved portion 260 of the arm 256 is also provided with a handle member 261 welded to the upper end thereof for manipulating the same.

The bearing members 250 and 251 rotatably support a shaft 263 on the left-hand end of which in Figure 1 a clutch member 264 is fixedly mounted. The shaft 263 is restricted at its ends to prevent endwise movement thereof. This clutch member 264 has a number of spaced pins 265 thereon which are adapted to be slidably inserted in the bores 235 in the clutch member 234 20 when the conveyor 252 is mounted on the universal mounting 210 in the manner heretofore described.

Assuming that the gear 161 in Figure 3 is in engagement with the gear 162 of the transmission 157, and that the clutch pedal 175 in Figure 1 has been moved in such a manner as to transmit motion to the gear 162, rotation will then be transmitted successively through shafts 152, 151, 142, 185, 190, 192 and 196 to the beveled gear 201 in Figure 12.

The beveled gear 201 will, in turn, transmit rotation to the gear 202 in Figure 5 thus causing the left-hand portion thereof to move towards the observer in Figure 12. The gear 202 will then transmit rotation to the gear 216 in a clockwise direction in Figure 12 to thus drive the shaft 217 in Figure 17, the sprocket wheel 225, the sprocket chain 226, the wheel 227 on the shaft 230 and the clutch member 234, which, of course, will cause the upper portion of the clutch member 234 to move towards the observer in Figure 17 or away from the observer in Figure 11. It is thus seen how the clutch member 234 will transmit rotation to the shaft 230 through the medium of the clutch member 264.

The shaft 263 has a conveyor roller 266 fixed thereon (Figures 11 and 13) on which an endless conveyor belt 267 is mounted. The belt 267 is also mounted on a roller 270 (Figure 1) which is rotatably mounted in adjustable bearing members 271 which are adapted to take up the slack in the belt 267 (Figure 1). An idler roller 268 is provided for supporting the lower reach of the conveyor belt 267 (Figure 10).

The manner in which the roller 270 is mounted is clearly shown in the patent to R. E. Wall, No. 2,107,682 of February 8, 1938, and a further description and showing of the same is, therefore, 60 deemed unnecessary.

The bearing blocks 271 in which the roller 270 is mounted for rotation are suitably secured to side walls 272 and 273 of a trough having a bottom 274 spanning the distance between the side walls 273 and 272. The bottom 274 is secured as by spot welding to a transverse plate 276 (Figure 13) which spans the distance between rearwardly and downwardly extending portions of the brackets 253 and 254. The upper reach of the conveyor belt 267 is supported between the rollers 266 and 270 by the bottom 274 of the trough and it will be noted in Figure 13 that there is a front wall member 281 secured to the side walls 272 and 273, as by welding, and spanning the distance therebetween. The lower

edge of this front wall 281 terminates a substantial distance above the upper reach of the conveyor belt 267 and a suitable resilient member 282 is secured to the wall 281 as by rivets 283, only one of which is shown in Figure 13 and this member 282 is adapted to engage the upper reach of the belt 267 to prevent the material which is dumped onto the conveyor adjacent this point from falling back through the opening defined by the lower edge of the front wall 281 and the upper reach of the conveyor belt 267.

In order that the material may be properly transferred or dumped from the opening at the rear end of the dump truck body 40 onto the upper reach of the conveyor belt 267, suitable walls 285, 286 and 287 (Figures 1, 11 and 13) are secured to the proximate surfaces of the side walls 272 and 273 of the trough and extend upwardly and outwardly at an angle to direct the material onto the conveyor belt 267. The front wall member 287 which is inclined at the same angle relative to the wall 281 as the side wall members 285 and 286 are inclined relative to the walls 272 and 273 and spans the distance between the members 286 and 285, the lower end of the same being extended downwardly into the trough to further insure that the material dumped from the truck bed 40 will enter the trough and be deposited onto the belt 267.

It has already been stated that the manner in which the gear housing 200, which supports the universal mounting 210, is connected to the chassis 13 of the truck, is a main feature of the present invention.

Since both sides of the gear housing 200 are mounted and connected to the chassis 13 in an identical manner, the side nearest the observer in Figures 4, 7 and 10 will be described and the side away from the observer in these figures will bear like reference characters with the prime notation added.

The gear housing 200 is secured as by screws 295 to the rearmost ends of longitudinally extending channel bars 296, 296' which are a part of a longitudinally movable frame broadly designated at 297. Referring to Figure 14, it may be observed that the bottom flanges of the channel bars 296 and 296' are welded intermediate their ends to a transverse frame member 300 which extends upwardly and outwardly at opposite ends thereof at an angle and is secured as by welding to relatively short longitudinally extending channel bars 301 and 301', the flanges of which extend outwardly with respect to each other. Welded to the front ends of the channel bars 301 and 301' in Figure 14 are remote ends of downwardly and inwardly angularly disposed portions of a cross frame member 304 which also spans the distance between the channel bars 296 and 296' and is welded to the upper flanges thereof. This completes the structure of the longitudinally movable frame 297 which supports the gear housing 200.

The channel bars 301 and 301' have longitudinal sliding movement between the flanges of longitudinally extending channel bars 305 and 305' (Figure 14) which are parts of an upper pivoted frame broadly designated at 306. Welded to the lower flanges of the channel bars 305 and 305' is an angle bar 307 and, in order to prevent dirt and other abrasive matter from falling from the dump truck bed 40 onto the proximate edges of the channel bars 301, 305 and 301' and 305', suitable shield plates 310 and 310' are welded to the proximate edges of the upper flanges of

the channel bars 305 and 305' and extend inwardly and downwardly at an angle, as shown in Figures 9 and 14.

Referring to Figures 5 and 10, it may be observed that the rearmost ends of the channel bars 305 and 305' have suitable stop plates 311 and 311' welded thereto to which the rearmost edges of the shield members 310 and 310', respectively, are also welded.

In Figures 4, 7 and 10, there is shown the manner in which the left-hand side of the pivoted frame 306 is connected to the chassis 13 of the truck. The right-hand side of the frame 306 being identical, will bear the same reference characters as the parts shown at the left-hand side of the truck with the prime notations added.

The channel bar 305 is pivotally connected at its left-hand end in Figures 4, 7 and 10 as at 313 to the lower end of a vertically disposed frame bar 314 which is secured as by screws 315 to the longitudinally extending channel member 14 of the chassis 13. The right-hand end of the channel bar 305 in Figures 4, 7 and 10 is pivoted as at 316 to the lower end of a substantially vertically disposed link member 317, the upper end of which is pivotally connected as at 320 to the rearmost end of the longitudinally extending channel bar 43 of the dump truck bed 40.

In order to prevent the pivoted frame 306 from swinging from side to side at its rearmost end in Figures 4 and 5, suitable strap iron members 322 and 322' are welded to the remote surfaces of the longitudinally extending channel bars 14 and 15 of the chassis 13 and extend downwardly and are bent inwardly and then are extended downwardly and slidably engage the remote vertical surfaces of the longitudinally extending channel bars 305 and 305' of the pivoted frame 306. It is thus seen that when the truck bed 40 is in the horizontal position shown in Figure 4, the housing 200 along with the frame 297 and the pivoted frame 306 are moved upwardly to thus provide a substantial clearance between the lower surfaces of the frame 297 and the housing 200 and the ground as the truck again moves from one place to another. A suitable thumb screw 323 threadably penetrates the web of the channel bar 305 (Figure 14) and bears against the web of channel bar 301 for holding the telescopic frame 297 in adjusted position relative to the pivoted frame 306.

When it is desired to use the conveying apparatus, as will be the case when the contents or material in the bed 40 must be delivered to a point remote from the truck, the conveying apparatus 252 is connected to the universal mounting 210 in the manner heretofore described, and, by moving the handle 182, for controlling the clutch pedal 175, forwardly, the power take-off 155 will transmit motion to the conveyor belt 267 in a clockwise direction in Figure 13 in the manner heretofore described. The longitudinally movable frame 297 with the universal mounting 210 and the gear housing 200 is then moved rearwardly to the position shown in Figures 4 and 10 to thus position the front end of the conveying apparatus 242 below the discharge end of the dump truck bed when it is in elevated or tilted position. Assuming that the bed 40 is in its normal horizontal position, the operator then grasps the handle 115 and manipulates the same in such a manner as to actuate the valve mechanism shown at 107 in Figure 18, and to thus cause the fluid in the hydraulic cylinder 81 to surge upwardly, inasmuch as the pump 105 will be driven

as heretofore described, thus causing the piston rod 84 to move upwardly and, in so doing, causing the truck bed to be tilted at its front end or moved from the position shown in Figure 4 to substantially the position shown in Figures 7 and 10.

Prior to or after tilting the bed 40, the operator grasps the handle 76 of the lever 72 and moves the same in a clockwise direction to thus move the door 67 upwardly and, then the material within the bed 40 will move, by gravity, through the opening 64 and will fall onto the upper reach of the belt 267, as shown in Figure 10, which will thus carry the material to a point remote from the truck.

Now in the event that the operator desires to dump the contents from the bed 40 immediately below the rear end of the same when it is in a tilted position as shown in Figure 7, the conveying apparatus 252 may be removed from the universal mounting 210, simply by moving the locking member 260 (Figure 11) away from the operator at its upper end and then sliding the conveying apparatus from left to right in Figure 11 to dis-engage the clutch members 254 and 234, after which the conveying apparatus 252 may be removed from the mounting 210.

The operator then pushes the rear end of the gear housing 200 in a forward direction and the channel bars 301 and 301' in Figure 12 will slide between the flanges of the channel bars 305 and 305' and the housing 200 is moved forwardly from the position shown in Figure 4 to the position shown in Figure 7. The door or cover 67 in Figure 5 is then raised in the manner heretofore described and the truck bed 40 is tilted from the position shown in Figure 4 to the position shown in Figure 7 and it is thus seen that the contents may be discharged from the opening 64 and will fall downwardly, by gravity, rearwardly of the rear end of the gear housing 200 and the associated mounting 210.

In order to permit the gear housing 200 to be moved longitudinally relative to the truck chassis 13, the telescoping shaft 192 is provided in the tubular shaft 190. It is obvious that an operator would merely reverse the procedure above described by manipulating the handles 115 and 182 at the rear of the truck when he desired to return the truck bed 40 from the tilted position shown in Figures 7 and 10 to the position shown in Figure 4 and when it is desired to stop movement of the conveyor belt 267.

It is thus seen that I have provided a universally mounted conveying apparatus for use with dump bed types of vehicular trucks wherein means are provided for positioning the conveyor immediately below a discharge opening at the rear end of the truck so that the contents may be dumped from the truck bed onto the conveyor and wherein other means are provided whereby the conveyor may be removed from the universal mounting and the universal mounting along with the gear housing from the conveyor may be moved beneath the chassis of the truck when it is desired to merely dump the material from within the truck bed onto the ground immediately therebelow.

I have further provided means whereby a single operator may control the action of the truck body and the driving of the conveying apparatus from a point at the rear of the truck, thereby eliminating the necessity of employing an additional operator in the operation of this apparatus.

In the drawings and specification there has been set forth a preferred embodiment of the invention, and although specific terms are employed, they are used in a generic and descriptive sense only, and not for purposes of limitation, the scope of the invention being defined in the claims.

I claim:

1. Material handling apparatus adapted to be mounted on a motor driven wheeled truck having a chassis and also having a dump bed mounted thereon and said dump bed also being pivoted near its rear end to the chassis and also having means for raising and lowering the front end to tilt the bed and said bed also having an opening in its rear end provided with a closure therefor and through which the contents of the bed may be dumped when its front end is raised relative to the chassis, said apparatus comprising a frame disposed beneath the rear end of the chassis and being pivoted to the chassis at its front end and also having upwardly projecting members at its rear end whose upper ends are pivotally connected to the bed, a telescopic frame slidably supported by the pivoted frame and being movable forwardly and rearwardly of the pivoted frame, a gear housing mounted on the telescopic frame and having a driving connection with the motor of the truck, means on the gear housing for supporting the forward end of a discharge endless conveyor and driving means between the gear housing and the forward end of the discharge conveyor for driving the discharge endless conveyor.

2. Material handling apparatus adapted to be mounted on a motor driven wheeled truck having a chassis and also having a dump bed mounted thereon, and said dump bed also being pivoted near its rear end to the chassis and also having means for raising and lowering the front end to tilt the bed and said bed also having an opening in its rear end provided with a closure therefor and through which the contents of the bed may be dumped when its front end is raised relative to the chassis, said apparatus comprising a frame disposed beneath the rear end of the chassis and being pivoted to the chassis at its front end and also having upwardly projecting members pivoted at their lower ends to the rear end of the telescopic frame and whose upper ends are pivotally connected to the bed at a point rearwardly of the pivot point between the bed and the chassis, a telescopic frame supported by the pivoted frame and being movable forwardly and rearwardly of the pivoted frame, a gear housing mounted on the telescopic frame and having a driving connection with the motor of the truck, means on the gear housing for detachably supporting the forward end of a discharge endless conveyor, driving means between the gear housing and the forward end of the discharge conveyor for driving the discharge endless conveyor, the telescopic frame together with its gear housing being movable forwardly of the truck, after the endless conveyor has been detached therefrom whereby the truck bed may be tilted to discharge the contents thereof through the opening in the rear end thereof so that the contents will fall clear of the gear housing.

3. Material handling apparatus comprising a motor driven wheeled truck having a chassis and a dump bed mounted thereon, said dump bed being pivoted near its rear end to the chassis and having means for raising and lowering the front end, and said bed having an opening in its rear

end and provided with a closure therefor and through which the contents of the bed may be dumped when its front end is raised relative to the chassis, a frame disposed beneath the rear end of the chassis and being pivoted to the chassis at its front end and also having upwardly projecting members pivotally secured thereto at its rear end whose upper ends are pivotally connected to the bed at a point rearwardly of the pivot point between the bed and the chassis, a telescopic frame supported by the pivoted frame and being movable forwardly and rearwardly of the pivoted frame, a gear housing mounted on the telescopic frame and having a driving connection with the motor of the truck, means on the gear housing for supporting the forward end of a discharge endless conveyor, driving means between the gear housing and the forward end of the discharge conveyor for driving the discharge endless conveyor, the gear housing comprising a base portion and a top portion mounted on a vertical axis for rotation relative to the base portion, and the means on the gear housing for supporting the forward end of the discharge endless conveyor permitting vertical swinging of the rear end of the conveyor.

4. In a wheeled truck having a chassis and an engine for propelling the truck and having a dump bed thereon pivoted near its rear end to the chassis and having means on the chassis connected to the front portion of the dump bed for raising and lowering the front portion of the dump bed, said dump bed having a discharge opening in its rear end and a suitable closure member for said discharge opening whereby the contents of the dump bed may be discharged through said opening when the front end of the dump bed is raised relative to the chassis, a frame disposed below the rear end of the chassis and having its forward end pivotally secured to the chassis and a pivoted link connection between the rear end of the frame and a point on the rear end of the dump bed disposed rearwardly of the pivot point of the dump bed whereby the rear end of the frame will be lowered and raised with the lowering and raising of the rear end of the truck bed, a telescopic frame supported by the first-named frame and having a gear housing thereon, intermeshing gears disposed within the gear housing, means connectable to the engine for driving the gears within the housing, said gear housing having means for supporting the forward end of an endless discharge conveyor and driving means disposed between the forward end of the discharge conveyor and the gears in the gear housing, said telescopic frame being movable forwardly and rearwardly relative to the chassis of the truck to cause the contents from the truck bed to be delivered onto the forward end of the discharge conveyor the forward end of the discharge conveyor being entirely removable from the gear housing whereby the gear housing and the telescopic frame may be moved forwardly relative to the chassis so that the contents of the truck bed may be discharged onto the ground on which the truck rests clear of the gear housing in telescoped position.

5. In a dump truck having a chassis and also having a bed mounted thereon and said bed also being pivoted near its rear end to the chassis and said truck also having means for raising and lowering the front end of the bed so as to tilt the bed and said bed also having a opening with a suitable closure therefor in the rear end of the bed and through which the contents of the bed

may be dumped, an improved unloading apparatus comprising forwardly and rearwardly movable means disposed below the chassis and having its front end pivotally secured to the chassis and having its rear end pivotally secured to the rear end of the bed and having means on its rear end for detachably supporting the forward end of an endless conveyor for receiving the material dumped from the truck and conveying it to a point remote from the truck, the means for driving the endless conveyor being movable forwardly relative to the chassis of the truck to a point where the contents discharged from the bed of the truck will fall clear of the means for driving the endless conveyor when the endless conveyor is removed therefrom.

6. An improved unloading apparatus for dump trucks, said dump truck having a wheeled chassis and also having an engine for propelling the same and also having a bed thereon provided with an opening in its rear end and being pivotally secured near its rear end to the chassis and also having means driven by the engine for raising and lowering the front end of the bed to dump the contents of the bed through the opening in the rear end thereof, said improved unloading apparatus comprising a frame pivoted at its front end beneath the rear end of the chassis and having a pivotal connection between the rear end of the pivoted frame and the extreme rear end of the bed whereby the rear end of the pivoted frame will be raised and lowered with the raising and lowering of the extreme rear end of the bed, a telescopic frame mounted for forward and rearward sliding movement in the pivoted frame and disposed at a lower level than the pivoted frame and having a vertically disposed shaft therein, said shaft having a gear wheel mounted therein on a vertical axis and having beveled gears on its lower and upper surfaces, a driving connection between the engine and the lower beveled gear on the gear wheel, means on the gear housing for supporting the forward end of an endless conveyor frame, a driving connection between the upper beveled gear on said gear wheel in the gear housing and the forward end of the endless conveyor for imparting movement thereto, the driving connection between the engine and the lower beveled gear on said gear housing being telescopic so that the telescopic frame along with its gear housing can be moved forwardly and rearwardly relative to the pivoted frame, said endless conveyor being detachably connected to the gear housing so that it can be entirely removed from the gear housing and then the gear housing with its telescopic frame may be moved forwardly relative to the pivoted frame so that the contents of the truck bed may be dumped through the opening in the rear end of the truck bed and fall downwardly clear of the gear housing mounted on the telescopic frame.
